UNITED STATES PATENT OFFICE.

RUSSELL E. BENNER, OF DETROIT, MICHIGAN, ASSIGNOR TO BURROUGHS ADDING MACHINE COMPANY, OF DETROIT, MICHIGAN, A CORPORATION OF MICHIGAN.

ADDING AND LISTING MACHINE.

1,115,889.

Specification of Letters Patent.

Patented Nov. 3, 1914.

Application filed December 20, 1909. Serial No. 534,101.

To all whom it may concern:

Be it known that I, RUSSELL E. BENNER, a citizen of the United States, residing at Detroit, in the county of Wayne and State 5 of Michigan, have invented certain new and useful Improvements in Adding and Listing Machines, of which the following is a specification.

The object of the present invention is to 10 provide means for showing automatically upon the printed record of work of adding and listing machines that the addition has exceeded the capacity of the machine and for enabling the user to determine from the 15 printed record to what extent the capacity of the machine has been exceeded, so that he will thus be enabled to arrive at the correct total.

In the use of the ordinary adding and listing machine it is common to run long lists 20 of items and the total is apt to exceed the capacity of the adding mechanism without the user having noticed that the total is running so high. In such case, with all of 25 the wheels showing numbers, the operator cannot be sure whether or not there has been an over-running.

By the present invention provision is 30 made for the printing of a special sign whenever the wheel of highest denomination completes a rotation and thus the user will be informed as to whether or not an over-running of the accumulator is to be taken into account in ascertaining the total.

35 In the form of embodiment of the invention here shown, means for carrying out the object are adapted to the well-known Burroughs type of adding and listing machine. A special type carrier is located at the left 40 of the usual series of amount type carriers and this special type carrier is put under control of the wheel of highest denomination. The latter, in completing a rotation, trips a pawl such as commonly used in the 45 Burroughs machine for transfer purposes and this pawl releases a latch corresponding to the latches ordinarily employed to hold down the transfer pawls. The latch so utilized is operatively connected to a detent or 50 controlling member for the special type carrier. The latter is normally withheld from printing position but in case of an over-addition is released so that in the ensuing operation of the machine the special sign will 55 be recorded at the left of the amount which

is printed thus indicating that a unit in an order or denomination beyond the capacity of the machine is to be taken into account in footing up the total.

While as stated the invention is here 60 shown especially adapted to the well-known Burroughs adding and listing machine, it is nevertheless to be understood that it is capable of adaptation to various other types of machines. 65

In the drawings which accompany and form part of this specification, Figure 1 represents in left-side elevation mechanism of the well-known Burroughs machine with an equipment for carrying out the present invention, all parts being illustrated as at normal; Fig. 2 shows in similar elevation certain of the parts which appear in Fig. 1 but under different conditions, to-wit, that obtaining when the operating handle of the 75 machine has been drawn forward but there has been no over-running of the addition; Fig. 3 is a similar view illustrating the changed relationship of parts when the handle of the machine has returned home and 80 an over-addition has taken place; Fig. 4 is another view of the same sort indicating the relationship of parts when the handle of the machine has been drawn forward after such over-running of the addition and when 85 the printing of the special sign takes place; Fig. 5 shows the special type carrier in right-side elevation detached; Fig. 6 is a top plan view of a portion of the machine including the special parts; and Fig. 7 shows 90 an example of work.

For the details of construction of the familiar Burroughs machine reference may be had to various prior patents, of which it will suffice to mention Nos. 504,963 and 95 505,078, issued September 12, 1893, on inventions of William S. Burroughs, and No. 913,860, issued March 2, 1909 on the invention of Jesse G. Vincent.

The numeral 916 designates the left-hand 100 pinion of the usual series of adding pinions in this type of machine and 610 the racks by which these pinions are turned, said racks being mounted through slot and pin and spring connections on the forward 105 ends of levers 611 independently pivoted on a central rock shaft 600 and at their rear ends carrying segmental series of sliding type plates 618.

The numeral 613 designates the usual re- 110

storing frame secured to the rock shaft 600 and vibrated in every operation of the machine and normally upholding the forward ends of the levers 611 and holding their rear ends downward with the types all below the printing line or the horizontal diametrical plane of the roller platen 17. The arrangement for controlling the extent of movement of the racks and for controlling the order of engagement and disengagement between the pinions and racks is well known and fully set forth in said prior patents and need not be here described. The transfer mechanisms for carrying tens from lower to higher order pinions is also of the familiar character and requires no special description and the same may be said of the impression means whereby the amount of types are driven against the platen.

In carrying out the present invention there is loosely mounted upon the rock shaft 600 just to the left of the highest order type carrying lever 611 a special type carrying arm A upheld by a spring a and notched as at a' to receive a pin b projecting from the adjacent type carrying lever 611. This arm A carries a single sliding spring-held type plate 618^a with a single type as clearly shown in Fig. 5, such type in the present instance being in the form of a cross or addition mark, though of course it may have any sort of a printing face. It is adapted to be driven against the platen by a hammer 715 constituting, as part of an impression mechanism, the duplicate of those which come into play in the printing of amounts and the construction and mode of operation of which is well understood and set forth in prior patents already mentioned. The arm A has an inclined shoulder a² similar to those common upon the regular type carriers and having the same mode of coöperation with the pawl 718 of the impression mechanism. It will be seen from the above that normally this special type carrying arm is restrained by the adjacent numeral type carrier and it will be understood that this causes the type 618^a to normally stand below the printing line as indicated in Fig. 1. So long as it occupies such a position or a position only slightly elevated, as will hereinafter be further explained, the inclined edge or shoulder a² will prevent the release of the hammer 715, in the usual manner. Whether or not the special type carrier is to advance to the printing line is determined by the degree of rotation of the wheel 916 of highest order. Ordinarily that wheel carries a trip or cam similar to those on the other wheels which serve to release or displace the usual transfer pawls, though the trip or cam on the highest wheel does not bring about any transfer operation since of course the highest wheel has no wheel to which its tens can carry. The cam

upon it therefore serves usually simply as a zero stop member. In the present instance a cam of this sort designated c is secured to the left side of the pinion 916 and coöperates with a pawl 413^a which is of the same construction and arrangement as what are commonly known as transfer pawls in the Burroughs machine. This pawl 413^a is connected by a spring c' with a latch 411^a which is just the same kind as those commonly known as transfer latches in the Burroughs machine. It performs the familiar function of holding out the pawl 413^a when the latter has been displaced by the cam c. This is illustrated in Fig. 3. Now the latch 411^a is connected to a long link C which at its rear end is connected to an arm C' secured to a rock shaft C², Figs. 1 and 6, the latter having also secured to it at the opposite or inner end an arm D for restraining the special type carrier A. This arm D has a hook formation at d and above that a straight front edge d' terminating at a horizontal shoulder d². Normally, as illustrated in Fig. 1, a stud a³ on the special type carrier extends below the hook shaped portion of the arm D, not, however, seating in the hollow of the hook but spaced therefrom so as to occupy a plane below the point of the hook. In the drawing forward of the operating handle all of the levers 611 move, as usual, at least to the extent of presenting zeros at the printing line. This movement of the left-hand lever 611 permits a slight rise of the special type carrying arm to the position shown in Fig. 2, where the stud a³ is shown seated in the hollow of the hook d, but the incline a² is still in position to disable the pawl 718. If, however, in the preceding operation the highest wheel 916 had passed the zero point, the pawl 413^a would have been displaced and the latch 411^a would have moved rearward over the pawl and would stand ready, under the impulse of the spring c', to swing the arm D rearward as soon as the special type carrier A moved down to normal at the conclusion of the succeeding operation, which condition is illustrated in Fig. 3, where the hook d is shown to have escaped rearwardly past the stud a³. In order to permit the immediate latching movement of the latch 411^a, notwithstanding the hood d is at the time interlocked with the stud a³, the link C is made with a short slot c³ where it connects with said latch 411^a, the latter having a stud c⁴ engaging said slot, see particularly Figs. 2 and 3. Now the condition having been arrived at which is illustrated in Fig. 3, it will be seen that in the next operation when the handle is pulled forward the special type carrier will rise unobstructed by the hook d of the arm D. In so doing its stud a³ passes up along the edge d' and lands against the horizontal shoulder d² as illus-

trated in Fig. 4 and this positions the type 618^a at the printing line. It furthermore carries the inclined shoulder α^2 above the pawl 718 so that at the conclusion of the 5 forward stroke of the operating handle the hammer 715 is released and the special type prints.

It will be understood that the pawl 411^a is restored along with the similar pawls and 10 by the usual form of mechanism. This comprises a bail 904 which swings forward as the operating handle comes to the end of its forward stroke and somewhat over-restores the latches to permit ample clearance for re- 15 engagement of the transfer pawls with these latches. Now it will be seen that this restoration of latches takes place at a time when the arm D is held against forward move- 20 ment, i. e., either with the stud α^3 seated in the hook d as shown in Fig. 2 or with said stud in front of the vertical edge d' as illustrated in Fig. 4. This condition necessitates a yielding form of connection between the link C and the arm C'. To this 25 end the rear portion of the said link is longitudinally slotted as shown at e and said arm C' has a stud e' engaging said slot and connected by a spring e² with the link. This spring stretches to a comparatively slight 30 extent when the latch 411^a is simply rocked forward as in Fig. 2 from its normal position. The spring stretches to a greater extent when the latch is rocked forward from its effective position, to-wit that illustrated 35 in Fig. 3. Fig. 4 shows the spring so stretched and ready to swing the arm D forward as soon as the special type carrier is returned to normal position which occurs when the handle returns home and the 40 frame 613 restores the lever 611, the pin b of the left-hand lever operating upon the special type carrier to carry its stud α^3 below the point of the hook d.

It will be seen that with the above de- 45 scribed construction whenever the highest wheel overruns the special type will be caused to print in the next operation.

Fig. 7 illustrates such a record as the machine, equipped with the special device, is 50 adapted to make, this record showing a series of items of large denomination which will cause over-running of the highest wheel in a number of instances. In order to figure the full total it is only necessary to count the 55 number of special marks at the left of the record, for this represents the number of times the highest wheel has over-run and consequently the number of digits in the highest order of the reel total. In the ex- 60 ample given the printed total is 4,302,920.66 but the wheels have overcarried five times as indicated by the mark at the left of items. Hence the full total is 54,302,920.66.

If the last item of the above example, in- 65 stead of being 345543211, was high enough

to cause another carry beyond the capacity of the machine, e. g., if the item was 945543211, then in the blank stroke required to be taken before the total is struck, the plus sign would print and appear on the 70 record opposite the blank space between the last added item and the total, or in the event a blank stroke was not required, then the plus sign would be printed along with the total. The full total in such case would 75 start with the numeral 6 instead of 5, since the plus sign would appear six times on the record.

While the above described construction is well adapted to the purpose it is susceptible 80 of modification within the scope of the invention.

What is claimed is:

1. In an adding and listing machine, the combination of a series of adding wheels, 85 means for differentially actuating the same, amount printing mechanism, and means under control of the adding wheel of highest order for recording to denote that the registering capacity of the wheels has been ex- 90 ceeded.

2. In an adding and listing machine, the combination of a series of adding wheels, means for differentially actuating the same, amount printing mechanism, a special type 95 carrier, and means for controlling the same by the adding wheel of highest order.

3. In an adding and listing machine, the combination of a series of adding wheels, 100 means for differentially actuating the same, amount printing mechanism, a special type carrier normally withheld from printing position, and means for releasing the same under control of the adding wheel of highest denomination.

4. In an adding and listing machine, the combination of a series of adding wheels, 105 means for differentially actuating the same, amount printing mechanism including amount type carriers, a special type-carrier 110 normally restrained by the adjacent amount type-carrier, a member for restraining said special type-carrier when said amount type carrier advances, and means controlled by the adding wheel of highest denomination 115 for disabling said member.

5. In an adding and listing machine, the combination of a series of adding wheels, 120 means for differentially actuating the same, amount printing mechanism including amount type carriers, a special type-carrier normally restrained by the adjacent amount type-carrier, a member for restraining said special type-carrier when said amount type-carrier advances, a latch connected to said 125 member, a pawl normally restraining said latch which when the pawl is displaced latches the same, and a trip on the wheel of highest denomination for displacing said pawl.

1
6. In an adding and listing machine, the combination of a series of adding wheels, means for differentially actuating the same, amount printing mechanism including amount type carriers, a special type-carrier normally restrained by the adjacent amount type-carrier, a hook for restraining said special type-carrier when the said amount type-carrier advances an advance of the special type carrier engaging it with the hook to restrain the latter, a latch operatively connected to said hook, a pawl normally restraining said latch which when the pawl is displaced latches the same, and a trip in the wheel of highest denomination for displacing said pawl.

7. In an adding and listing machine, the combination of a series of adding wheels, means for differentially actuating the same, amount printing mechanism including amount type carriers, a special type-carrier normally restrained by the adjacent amount type-carrier, a pivoted hook for restraining said special type carrier when the said amount type-carrier advances an advance of the special type carrier engaging it with the hook to restrain the latter, a latch operatively connected to said hook, a pawl normally restraining said latch which when the pawl is displaced latches the same, and a trip on the wheel of highest denomination for displacing said pawl.

8. In an adding and listing machine, the combination of a series of adding wheels, means for differentially actuating the same, amount printing mechanism, including amount type carriers, a special type-carrier normally restrained by the adjacent amount type-carrier, a pivoted hook for restraining said special type carrier when the said amount type-carrier advances an advance of the special type carrier engaging it with the hook to restrain the latter, a latch, a pawl normally restraining said latch which when the pawl is displaced latches the same, a trip on the wheel of highest denomination for displacing said pawl, and a link connecting the latch and the hook with lost motion provisions.

9. In an adding and listing machine, the combination of a series of adding wheels, means for differentially actuating the same, amount printing mechanism, including

amount type carriers, a special type-carrier normally restrained by the adjacent amount type-carrier, a pivoted hook for restraining said special type carrier when the said amount type-carrier advances an advance of the special type carrier engaging it with the hook to restrain the latter, a latch, a pawl normally restraining said latch which when the pawl is displaced latches the same, a trip on the wheel of highest denomination for displacing said pawl, and a link having a slot and pin connection with said latch and a connection with the hook.

10. In an adding and listing machine, the combination of a series of adding wheels, means for differentially actuating the same, amount printing mechanism, including amount type carriers, a special type-carrier normally restrained by the adjacent amount type-carrier, a pivoted hook for restraining said special type carrier when the said amount type-carrier advances an advance of the special type carrier engaging it with the hook to restrain the latter, a latch, a pawl normally restraining said latch which when the pawl is displaced latches the same, a trip on the wheel of highest denomination for displacing said pawl, and a link having a slot and pin and spring connection with the hook and a connection with the latch.

11. In an adding and listing machine, the combination of a series of adding wheels, means for differentially actuating the same, amount printing mechanism, including amount type carriers, a special type-carrier normally restrained by the adjacent amount type-carrier, a pivoted hook for restraining said special type carrier when the said amount type-carrier advances an advance of the special type carrier engaging it with the hook to restrain the latter, a latch, a pawl normally restraining said latch which when the pawl is displaced latches the same, a trip on the wheel of highest denomination for displacing said pawl, and a link having a slot and pin and spring connection with the hook and a slot and pin connection with the latch.
